[57] ABSTRACT

[21] Appl. No.: 228,698

A yarn tension controller and slub catcher includes discs between which yarn may be fed to a knitting machine, adjustable spring means for urging one disc toward the other to maintain a predetermined tension in the yarn, and adjustable stop means for limiting the distance by which the discs may be separated by a slub acting against the discs and thereby the effective size of a yarn guide located between the discs.

YARN TENSION CONTROLLERS AND SLUB CATCHERS

BACKGROUND OF THE INVENTION

1. Field of the Invention

The invention relates to knitting machines and more particularly to yarn tension controlling means and yarn slub catchers.

2. Description of the Prior Art

Yarn tension controlling devices and yarn slub catchers are well known in the knitting art. It is common practice, for example, to pass yarn being fed to the needles of a knitting machine, between discs which are pressed together by adjustable spring means and in this manner control tension in the yarn. It is also common practice to provide slub catchers in the form of eyelets situated between yarn cones and stop motion devices.

SUMMARY OF THE INVENTION

In accordance with the invention, discs between which yarn is caused to pass are used not only to control tension in the yarn, but in conjunction with a stop limiting separation of the discs and thereby the effective size of a yarn guide opening, to prevent slubs or yarn from passing through the device of the invention and so result in the actuation of a stop motion device in a well known manner. Spring means biases one disc toward the other and means are provided for adjusting the spring means to thereby change tension in the yarn. A stop which is adjustable to accommodate various and sundry forms of yarn limits the distance by which the discs may be separated by a slub acting on the discs and the effective size of a yarn guide opening to thereby prevent yarn slubs from passing to the knitting needles of a machine to which the yarn is fed.

It is an object of the invention to provide an improved yarn controlling device for a knitting machine capable of serving both as a yarn tension controller and slub catcher.

It is another object of the invention to incorporate yarn tension controlling and slub catching functions in a single device wherein certain of the elements thereof perform a dual function.

It is still another object of the invention to provide improved adjustable slub catching means.

Other objects and advantages of the invention will become apparent during a reading of the specification when taken in connection with accompanying drawings.

DESCRIPTION OF THE DRAWINGS

FIG. 1 is a perspective view showing the yarn tension controller and slub catcher of the invention.

FIG. 2 is a longitudinal sectional view on a substantially vertical plane taken through the axis of the device.

FIG. 3 is a sectional view taken on the plane of the lines 3-3 of FIG. 2.

FIG. 4 is a view similar to FIG. 3 showing a yarn slub in the device of the invention.

FIG. 5 is a cross-sectional view taken through the yarn guide opening in the device of the invention and showing a yarn slub caught in the device.

DESCRIPTION OF THE PREFERRED EMBODIMENT

Referring to the drawings, reference character 10

designates the yarn tension controller and slub catcher of the invention. Such device includes an arm 12 from which a flange 14 extends at right angles. Affixed to the flange 14 at 16 is a spring clip 18 by means of which the device of the invention may be mounted on the superstructure of a circular knitting machine as between a yarn cone and stop motion device.

A shaft 20 is affixed to arm 12 at 22 and extends at right angles to planar face 24 of the arm. A portion 26 of the shaft adjacent to arm 12 is rectangular in cross section and includes an opening 28 which extends through the shaft. A portion 30 of the shaft, extending to one side of rectangular portion 26 is circular in cross section and includes screw threads 32. Plate-shaped discs 34 and 36 are slidable on shaft 20 with which they have a loose fit. A spring 38 located between disc 36 and a knob 40 biases the disc 36 toward disc 34 and maintains the disc in a position wherein the disc 34 contacts planar face 24 of the arm 12.

Knob 40 has a threaded connection with the screw threads 32 and when turned moves toward or away from the disc 36 according to the direction of turning to adjust the compressive force of spring 38 and so increase or decrease respectively the force of spring 38 on the disc 36. A boss 42 also has a threaded connection with screw threads 32 and may be turned to any selected position defining a limiting position for the disc 36, i.e., a position into which the disc 36 may be moved against the bias of spring 38 and wherein the disc 36 squarely contacts the end surface 44 of boss 42. The proper position of the boss depends upon the type of yarn in use and the magnitude of the slubs therefore likely to be encountered. The boss 42 is properly positioned when so located that with disc 36 against end surface 44 of the boss 42, the disc extends over opening 28 decreasing the effective cross-sectional area of the opening sufficiently to prevent yarn slubs from passing through it. In order to facilitate turning, the boss is provided with opposed planar faces 46 and 48 which may be engaged with a wrench.

Yarn 50 is fed through the device of the invention, as in the direction indicated, to pass between, the discs 34 and 36 and through opening 28 in the shaft 20. Tension is imparted to the yarn leaving the device, by the pull of the knitting machine to which the yarn is fed, and to a degree dependent upon the frictional force exerted upon the yarn by the discs 34 and 36. Turning knob 40 is in a direction to increase the compression of spring 38 and thereby the force exerted by the discs 34 and 36 upon the yarn results in an increase in tension in the yarn, whereas turning the knob in a direction to decrease the compression of the spring and the force exerted on the yarn by the discs decreases tension in the yarn. A slub 52 in yarn being fed to the discs 34 and 36 tends to move disc 36 apart from disc 34 and unless the slub is unusually large it finds its way into the space between the discs by slightly tilting disc 36 relative to disc 34. The slub is flattened somewhat in the space between the discs by the pressure of the discs and moves to the opening 28. With the boss 42 properly set, the yarn slub 52 is prevented from passing through the opening 28 because of the reduced effective area of the opening (FIG. 4) and actuations of a stop motion device may thereby be provided for. An unusually large slub would of course be stopped by the discs before reaching the hole 28 to provide for the actuation of the stop motion device.

While the invention has been described in its preferred form, it is to be understood that the words which have been used are words of description rather than of limitation, and that changes within the purview of the appended claims may be made without departing from the true scope and spirit of the invention.

Having thus described the nature of the invention, what is claimed herein is:

1. A yarn tension controller and slub catcher for a knitting machine, said yarn controller and slub catcher comprising an elongated member having a hole extending transversely therethrough through which yarn fed to said machine must pass, a pair of discs mounted on said elongated member and between which yarn may be fed to said machine, at least one of said discs being axially movable so as to be extendible over at least a portion of said hole to thereby decrease the effective cross-sectional area thereof, spring means for urging one disc toward the other whereby the discs may be caused to press against the yarn, means for adjusting the spring to change tension in the yarn and slub stopping means including means limiting the distance by

which said discs may be separated by a slub acting on the discs and against the bias of said spring means.

2. The yarn tension controller and slub catcher of claim 1 wherein said limiting means is adjustable.

3. The yarn tension controller and slub catcher of claim 1 wherein the limiting means includes a stop member having a threaded connection with the elongated member such that the position of said stop on the elongated member can be adjusted to define a limiting position over said hole for one of said discs.

4. The yarn tension controller and slub catcher of claim 3 wherein the spring adjusting means has a threaded connection with said elongated member and may thereby be positioned on said member to predetermine the compression of said spring.

5. The yarn tension controller and slub catcher of claim 4 wherein the spring is concentric with and extends over the stop member, has one end in engagement with the spring adjusting means and the other end in engagement with a disc.
